UNITED STATES PATENT OFFICE.

EMMANUEL DOBROWSKY, OF NEW YORK, N. Y.

ELECTRODE CONSTRUCTION.

Application filed January 20, 1925. Serial No. 3,656.

This invention relates to electrodes for lighting and heating purposes.

An object of the invention is to provide a simple and efficient electrode for lighting and heating purposes whereby the electrodes burn more uniformly and the arc consequently is more continuous and requires no controlling mechanism.

Another object concerns the provision of means whereby the electrodes, after they are once related to each other and the arc is established, will maintain the arc continuously until the electrodes are substantially entirely consumed, unless the circuit is opened before its complete consumption takes place.

The invention is illustrated in the drawings, of which—

Figure 1 is a side elevation, with portions broken away, of one form of my invention;

Fig. 2 is a section on the line 2—2 of Fig. 1;

Fig. 3 is a similar elevation of a modified form of the invention;

Fig. 4 is a section taken on the line 4—4 of Fig. 3; and

Fig. 5 is a similar section taken through a modified form of the apparatus.

The forms of the invention shown in the drawings are preferred forms, although it is understood that other modifications in the construction and arrangement of the parts and in the character of the materials used may be adopted without departing from the spirit of the invention as set forth in the appended claim.

In its general aspect the invention comprises providing a pair of electrodes, one preferably embracing the other and both arranged symmetrically with respect to a given axis. The preferred form of the invention generally comprises a tubular electrode and a rod electrode associated therewith in line with the axis of the tube so that there is an annular cylindrical gap between the electrodes throughout their length. These electrodes are maintained in this relation by suitable insulating means spacing them and supporting them, preferably at one end.

In another form of the invention I may provide two concentric tubular electrodes, one within the other, and also provide a bar of metal, preferably centrally disposed and

preferably of magnetic metal to exert a steady influence on any arc formed between the tubes.

The preferred form of the invention shown in the drawings, as represented by Fig. 1, comprises a tube 10, preferably of carbon, and a rod 11, preferably of the same material. The rod is disposed centrally with respect to the axis of the tube and is supported in this relation by a plate 12 of insulating material disposed between the two electrodes in any desired manner.

In Fig. 3 I show two tubes 13 and 14, preferably of carbon, and a central bar 15 of metal, preferably magnetic metal, which are suitably spaced from each other, as shown, by rings 16 and 17 of insulation. The bar or rod 15 of metal is provided to exert a steady directional control over the arc formed between the two tubular electrodes. This control element 15 may also be an electrode similar to electrodes 13 and 14. This particular arrangement would be applicable for polyphase alternating current operation. The number of concentric electrodes is not to be limited to a single-phase operation.

In Fig. 5 I show a sectional view of a tubular electrode 18 and an oval bar electrode 19 which are concentrically disposed and form an annular oval-shaped gap across which the arc is formed.

It is obvious that by providing a proper difference of potential between the two or more electrodes in any one of these forms, or other concentric forms, an arc is established therebetween, preferably near the open ends, and this arc will travel around the annular gap. The arc may be struck mechanically by means of a conductor short circuiting the ends of the electrodes cross sectionally. As the electrodes, due to the heat and the volatilization of the carbons or composite material, become separated the arc will, nevertheless, continue because the gap extends, as shown, the full length of the electrode and there is no interruption in the arc due to the failure of the gap, nor is there any interruption to the arc due to a variation in the gap, since the width of the gap remains constant. In the case of tubular electrodes, the arc is sometimes found to be steadier when the bar of magnetic material is disposed, preferably, in the manner shown in Fig. 3. By reason of the continuity of

the arc and the steadiness thereof this form of electrode is especially suitable for lighting and heating purposes. The continuity and steadiness of the arc enable it to be used without any of the complicated and erratically operating electro-magnetic controlling devices now in use in connection with arc light and heating apparatus.

What I claim is:—

An electrode construction which comprises a plurality of tubular electrodes, one disposed within the other, a central bar of magnetic metal within the inner tube, and insulating means for supporting the tubes and the bar from each other.

EMMANUEL DOBROWSKY.
